US0D1097908S

(12) **United States Design Patent** (10) **Patent No.:** **US D1,097,908 S**
(45) **Date of Patent:** **** Oct. 14, 2025**

(54) **AUTOMOTIVE RADIATOR**

(71) Applicant: **Resource Intl Inc.**, New Castle, DE (US)

(72) Inventor: **Daniel Tafe**, Newark, DE (US)

(73) Assignee: **Resource Intl Inc.**, New Castle, DE (US)

(**) Term: **15 Years**

(21) Appl. No.: **29/921,793**

(22) Filed: **Dec. 19, 2023**

(51) LOC (15) Cl. **12-16**

(52) U.S. Cl.

USPC **D12/166**

(57) **CLAIM**

The ornamental design for an automotive radiator as shown and described.

DESCRIPTION

FIG. 1 is a top front perspective view of the automotive radiator according to the present application;

FIG. 2 is a top rear perspective view of FIG. 1;

FIG. 3 is a front view of FIG. 1;

FIG. 4 is a rear view of FIG. 1;

FIG. 5 is a top view of FIG. 1;

FIG. 6 is a bottom view of FIG. 1;

FIG. 7 is a side view of FIG. 1; and,

FIG. 8 is a side view of FIG. 1.

The broken line showing is included for the purpose of illustrating unclaimed subject matter and forms no part of the claimed design.

The shade line showing is included for the purpose of illustrating contour and not surface ornamentation.

1 Claim, 6 Drawing Sheets
